UNITED STATES PATENT OFFICE

ABRAHAM SHAPIRO, OF CHICAGO, ILLINOIS, ASSIGNOR TO UNIVERSAL STAMPING & MFG. CO., OF CHICAGO, ILLINOIS, A CORPORATION OF ILLINOIS

SAFETY SHUTTER FOR CINEMATOGRAPHS

Application filed April 2, 1930. Serial No. 441,019.

The main objects of this invention are to provide an improved form of cinematograph; to provide a cinematograph having an improved form of safety shutter adapted 5 to move automatically into the path of light to interrupt some of the light rays of the lamp immediately upon the stopping of the light interceptor so as to permit the showing of a "still" picture without injury to 10 the film; to provide improved mechanism operable by the light interceptor for quickly moving the safety shutter out of the path of light when the interceptor commences to rotate; and to provide a safety shutter having 15 improved means for dissipating much of the heat in the path of light.

An illustrative embodiment of this invention is shown in the accompanying drawings, wherein:—

20 Figure 1 is a fragmentary side elevation of the front portion of a cinematograph casing with the side plate removed so as to show the operating mechanism.

Fig. 2 is an enlarged fragmentary trans- 25 verse section taken on the line 2—2 of Fig. 1.

Fig. 3 is a longitudinal section, taken on the line 3—3 of Fig. 2, showing the safety shutter in operative position for screening the light rays.

20 Fig. 4 is a view similar to Fig. 3, but showing the safety shutter in the position which it occupies while the interceptor is rotat- 30 ing.

Fig. 5 is a perspective of the safety shutter.

35 Fig. 6 is a fragmentary side elevation, taken from the right of Fig. 2 but showing the parts in the positions which they occupy during the rotation of the interceptor.

Fig. 7 is a vertical section, taken on the 40 line 7—7 of Fig. 2; the drum being omitted.

Fig. 8 is a detail, partly in elevation and partly in section, showing the safety shutter and its operating means.

The accompanying drawings show only 45 those portions of a projector which are believed necessary to a thorough apprehension of the invention. The improved safety shutter, to which this invention is applied, may be used in connection with many different 50 types of cinematographs. In the construc-

tion illustrated, the safety shutter is applied to a machine of the type shown in my co-pending application, Serial No. 374,630, filed June 29, 1929, in the name of Abraham Sapier.

55 Cinematographs generally include an upright casing on which is mounted a rotatable light interceptor between light bulb and the film guideway. The film is supported on a pair of reels and is usually fed from the feed reel to the take-up reel by a pair of continuously driven sprockets. As the film passes through the guideway, an intermittent motion is imparted to it by suitable means, such as a reciprocating claw, for momentarily positioning each picture directly in the path of light.

60 When the exhibition of what is known as a "still" picture is desired, it is necessary to stop the film feeding means and light interceptor. If the film is stopped and the interceptor is positioned out of the path of light for the purpose of exhibiting a "still" picture, the heat of the lamp is likely to blister 65 the film unless the light rays are screened. For this reason, high grade projectors are 70 equipped with a fire shutter or safety shutter which is movable into the path of light for screening the light rays when the interceptor is stopped.

75 In the construction herein shown, the casting of the machine, which is only partly shown, includes a side wall 1 having a gear housing 2 formed at its front end for housing a train of gears which drives the light interceptor, feeding claw, and film sprockets. A removable plate, not shown, is secured to the gear housing by screws 3. Formed on the front end of the gear housing, 80 are lugs 4, on which are pivoted the arms, 85 not shown, for supporting the film reels.

90 The train of gears in the housing includes gears 5 and 6 mounted on shafts 7 and 8, respectively, which support the film feeding sprockets, not shown. The gears 5 and 6 mesh with a gear 9 driven by a pinion 10 on a shaft 11 which supports a gear 12. The gear 12 is driven by a pinion 13 fast on a main drive shaft 14. The pinion 13 also 95 meshes with a gear 15 mounted on a shaft 100

16 which actuates the film feeding claw, not shown.

Also mounted on the drive shaft 14, is a gear 17 which drives a gear 18 secured to 5 one end of a hollow shaft 19 supported in bushings 20 in a bearing 21 formed on the wall 1.

Extending laterally from the wall 1 on the side opposite the gear housing, is a front 10 wall 22 having a light aperture 23, and a middle partition 24 which supports the usual condenser 25. A lamp 25.1 is located in a compartment behind the condenser.

Located in the front compartment of the 15 casing, is a cup-shaped shell 26 having diametrically opposed apertures 27 and 28 in alignment with the condenser 25 and aperture 23. The shell is concentric with respect to the shaft 19, and its base is rigidly secured 20 to the wall 1.

Located within the shell 26, is a rotatable drum interceptor 29 having a pair of arms 30 adapted to move transversely through the horizontal path of light for interrupting 25 the light rays passing outwardly through the shell. The base of the interceptor is secured to the inner reduced end of the shaft 19 by means of a nut 31 threaded on the shaft.

30 The improved safety shutter herein shown is disposed coaxially with respect to the interceptor and is adapted to be operatively connected to the interceptor by an improved centrifugal clutch, which is operable upon 35 rotation of the interceptor for shifting the shutter out of the light path.

In the form shown, the improved safety shutter comprises an arm 32 provided with an elongated aperture 33 for receiving one 40 end of a shaft 34, which is rotatably supported within the hollow shaft 19. The shutter is secured to the shaft 34 by a screw 35.

Formed on one end of the arm 32, is a clip 36, which supports a transparent disk 37 45 formed preferably of heat resisting glass. The disk 37 is disposed at substantially right angles to the arm 32 and is movable into the path of light directly behind the apertures 28 and 23 as shown in Fig. 3. Mounted on 50 the inner face of the disk 37, is a wire mesh 38 which dissipates much of the heat of the light rays so as to prevent injury to the film when the shutter is in operative position. A counter weight 39 is mounted on the opposite 55 end of the arm 32.

The shaft 34 is preferably reduced at its central portion to provide an oil chamber 40 communicating with an oil supply pipe 41 through a port 42 in the shaft 19 and a chamber 43 located between the bushings 20.

The improved centrifugal clutch, which is adapted to connect the safety shutter with the interceptor, includes the gear 18 and a drum 44 which is fast on the shaft 34. 65 Formed on the gear 18, adjacent the drum, is

a hub 45 which is recessed to form a guide-way 46 for a pair of radially movable governor bodies 47, which, upon rotation of the gear 18, are thrown into frictional engagement with the drum 44 for shifting the safety shutter out of the light path. The weights 47 are secured to the gear 18 by pins 48 engaging radial slots 49 in the gear.

Embracing the periphery of the hub 45, is a spring wire 50 which engages the weights 47 for quickly retracting these weights upon the stopping of the gear 18.

Mounted on the outer face of the drum 44, is a sheet metal plate 51 which has a lug 52 struck out therefrom for engaging an aperture 53 in a link 54. Formed in the link 54, is a slot 55 for receiving a stop pin 56 mounted on the wall 1 for securing the safety shutter against rotation beyond the vertical position shown in Fig. 4. Secured to the upper 80 end of the link 54, is a spring 57 which is fastened to the casing so as to quickly restore the safety shutter to the operative position 85 shown in Fig. 3 when the interceptor ceases rotating.

In the operation of this improved projector, the film is fed downwardly in front of the light aperture 23 by means of the sprockets and feeding claw, not shown, which are driven by the train of gears in the 90 housing 2. During the normal operation of the machine, the gear 18 rotates the interceptor 29 continuously for interrupting the light rays.

As soon as the gear 18 starts to rotate for 100 driving the interceptor, the bodies 47 are thrown outwardly by centrifugal action so as to frictionally engage the drum 44, whereupon the drum is rotated for shifting the safety shutter 32 out of the light path. Rotation of the drum 44 is limited by the stop pin 56, which engages the link 54, so as to secure the safety shutter against movement beyond the vertical position shown in Fig. 4. After the drum is stopped by the link 54, the 105 governor bodies 47 on the rotating gear 18 merely slip on the periphery of the drum.

Upon the stopping of the drive shaft 14, as for instance, when it is desired to display a "still" picture, the spring 50 urges the weights 47 inwardly out of contact with the drum and the spring 57 quickly shifts the safety shutter to the position shown in Fig. 3. When the disk 37 and screen 38 are positioned in the light path directly behind the light aperture, much of the heat is dissipated and the film may be held any length of time without injury.

Although but one specific embodiment of this invention has been herein shown and described, it will be understood that numerous details of the construction shown may be altered or omitted without departing from the spirit of this invention as defined by the following claims.

I claim:

1. In a cinematograph, a casing having a light aperture, illuminating means behind said aperture for directing light rays through said aperture, a rotatable member between said means and said aperture, a glass disk carried by said member and movable thereby into the path of light, a metallic fo-
5 raminous screen mounted on one side of said disk for dissipating some of the heat of the rays, and mechanism for rotating said member.
2. In a cinematograph, a casing having a light aperture, a lamp behind said aperture for directing light rays forwardly, a safety shutter comprising a rotatable arm, a clip on one end of said arm, a glass disk supported on said clip and movable into and out of the path of light behind said aperture, a wire
10 mesh screen mounted on one face of said disk for dissipating some of the heat of the rays, and mechanism for rotating said shutter.
3. A cinematograph comprising a casing having a light aperture, illuminating means behind said aperture, a light interceptor located between said means and aperture and adapted to be rotated through the path of light for interrupting the light rays, operating mechanism for actuating said interceptor, a rotatable safety shutter movable into the path of light behind said aperture, a pair of clutch elements connected respectively to said interceptor and shutter, a pair of governor bodies connected to one of said
25 elements and movable radially into frictional engagement with the other of said elements for rotating said shutter out of the light path upon the rotation of said interceptor, means limiting the rotation of said shutter, and a spring engaging said other element for normally shifting said shutter into the path of light.
4. A cinematograph comprising a casing having a light aperture, illuminating means behind said aperture, a light interceptor located between said means and aperture and adapter to be rotated through the path of light for interrupting the light rays, operating mechanism for actuating said interceptor, a rotatable safety shutter movable into the path of light behind said aperture, said operating mechanism including a gear connected to said interceptor for driving said interceptor, a rotatable clutch element connected
40 to said shutter, and a pair of radially movable governor bodies carried directly on said gear and movable into frictional engagement with said clutch element for rotating said shutter out of the light path upon the rotation of said interceptor.
5. A cinematograph comprising a casing having a light aperture, illuminating means behind said aperture, a light interceptor located between said means and aperture and adapted to be rotated through the path of
45
- light for interrupting the light rays, operating mechanism for actuating said interceptor, a rotatable safety shutter movable into the path of light behind said aperture, said operating mechanism including a gear connected to said interceptor, a rotatable clutch element connected to said shutter, a pair of radially movable governor bodies connected to said gear and movable outwardly into frictional engagement with said clutch element for rotating said shutter out of the light path upon the rotation of said interceptor, and a spring connected to said clutch element for normally urging said shutter into the path of light.
6. A cinematograph comprising a casing having a light aperture, a lamp behind said aperture for directing light forwardly through said aperture, a pair of concentrically arranged shafts rotatably mounted on said casing, a light interceptor mounted on one of said shafts and located between said lamp and aperture for interrupting the light rays, a safety shutter mounted on the other of said shafts between said lamp and aperture, operating mechanism including a gear on the interceptor shaft, pins on said gear, a clutch drum on the shutter shaft, a pair of radially movable governor bodies directly carried by said pins and movable into frictional engagement with said drum for shifting said shutter out of the light path upon rotation of said interceptor, and means engaging said drum for limiting its rotation.
7. A cinematograph comprising a casing having a light aperture, a lamp behind said aperture for directing light forwardly through said aperture, a pair of concentrically arranged shafts rotatably mounted on said casing, a light interceptor mounted on one of said shafts and located between said lamp and aperture for interrupting the light rays, a safety shutter mounted on the other of said shafts between said lamp and aperture, operating mechanism including a gear fast on the interceptor shaft for driving said interceptor, a clutch drum on the shutter shaft, a pair of radially movable governor bodies mounted directly on said gear and adapted to frictionally engage said drum for shifting said shutter out of the light path upon rotation of said interceptor, and a spring yielding restraining the outward movement of said bodies.
8. A cinematograph comprising a casing having a light aperture, a lamp behind said aperture for directing light forwardly through said aperture, a pair of concentrically arranged shafts rotatably mounted on said casing, a light interceptor mounted on one of said shafts and located between said lamp and aperture for interrupting the light rays, a safety shutter mounted on the other of said shafts between said lamp and aperture, operating mechanism including a gear on the in-

terceptor shaft, a clutch drum on the shutter shaft, a pair of radially movable governor bodies mounted on said gear and adapted to frictionally engage said drum for shifting
5 said shutter out of the light path upon rotation of said interceptor, a link connected to said drum, a stop engaging said link for limiting the rotation of said shutter, and a spring engaging said link for urging said shutter into the light path upon the stopping of said gear.

Signed at Chicago this 31st day of March, 1930.

ABRAHAM SHAPIRO.
